[57] CLAIM

The ornamental design for a weight alarm digital scale,
as shown and described.

DESCRIPTION

FIG. 1 is a front and top-left perspective view of a
weight alarm digital scale showing my new design;
FIG. 2 is a left side elevational view thereof, the right
side view being a mirror image thereof;
FIG. 3 is a rear elevational view thereof;
FIG. 4 is a front elevational view thereof;
FIG. 5 is a bottom plan view thereof.
